EDWARD B. CAMPBELL, OF ST. LOUIS, MISSOURI, ASSIGNOR TO WILLIAMS PATENT CRUSHER AND PULVERIZER CO., OF ST. LOUIS, MISSOURI, A CORPORATION OF MISSOURI.

REDUCING-MILL

1,315,281. Specification of Letters Patent. Patented Sept. 9, 1919.

Application filed February 10, 1919. Serial No. 278,166.

To all whom it may concern:

Be it known that I, EDWARD B. CAMPBELL, a citizen of the United States, residing at St. Louis, State of Missouri, have invented 5 certain new and useful Improvements in Reducing-Mills, of which the following is a specification.

This invention relates to certain new and useful improvements in reducing mills having especial reference to rotary hammers for mills used for grinders feed cutters and like reducing mills, the peculiarities of which will be hereinafter described and claimed.

The main object of my improvements is 15 the provision of a flat bar rotary hammer forming a long, thin operative edge at front and rear operating in the cylindrical curved plane of rotation of the head, which head is formed at right angles to the leg by which 20 it is pivoted so that said hammer may be mounted in multiple in a rotor and thus secure a more flexible action on the material fed to said mill than the so called "stirrup hammer" that has a long operative edge extending between two legs by 25 which it is pivoted.

In the accompanying drawing on which like reference letters indicate corresponding parts, Figure 1 represents a vertical sectional view of the housing of a mill and rotor embodying my improvements, the section being taken across the shaft; Fig. 2 a partial sectional view of the housing taken in a vertical axial plane, and face view of 30 part of the rotor with hammers of my style mounted thereon and showing a half length head to fill out alternate rows; Fig. 3 a detailed perspective view of a hammer shown in Fig. 2; Fig. 4 a similar view of a hammer 35 with a sharpened edge; and Fig. 5 a similar view of a hammer of three pieces riveted together through line 28; Fig. 6 a similar view of a half length head hammer to fill out a row of T-head hammers; and Fig. 7 a perspective view of a cast T-head showing trunnions.

The letter A designates the housing and B the hopper of a suitable mill in which is mounted the shaft C, carrying pairs of disks 50 D keyed to said shaft and in which are mounted hammer rods E, on which are pivoted hammers of the construction and shape now to be described. A suitable cage F and breaker plate G is provided for coöperation with said hammers.

The disks D are mounted in pairs or series along the shaft C, and between each pair of disks the flat bar legs H of my hammers are mounted as shown in Fig. 2. The flat bar of which the hammer is composed, is of relatively greater width than thickness, and the head I is likewise formed of a flat bar and mounted on said leg so that the head extends laterally at right angles to the flat side of said leg substantially a distance equal to the length of the leg, thereby presenting the lesser dimensions of the bar in both the leg and the head to form the operative edge of head and leg. The flat bar used preferably to form the leg, is 60 doubled in its lesser dimension or thickness, and the head is likewise doubled and may be riveted together or otherwise fastened so as to constitute one piece and form a T head. As shown in Fig. 3, this form of hammer is 65 made from one piece of flat bar that is bent and doubled in layers to form a T head hammer. In Fig. 4 the upper layer of the head is beveled or sharpened at its front and rear edge on its outer side, to form a cutting edge and allow of its being reversed and either edge used as the forward cutting edge for the time being. In Fig. 3 the operative edge is plain and square.

Referring to Fig. 2 it will be seen that 70 the T heads of the hammers form rows parallel to the shaft, on account of their being mounted alternately on the rods E as shown in Fig. 1. That is to say, the heads of the respective hammers in one row overlap the 75 path of the following hammers in another row, while they form a long cutting edge that is broken up into individual units and give flexibility in their operation on the material. Thus if a piece of material is struck 80 by one hammer, this hammer will be pressed backward without influencing the cutting action or slicing action of the other hammers in the same row which are not acting on this chunk of material, such as bulbs, beets, turnips, etc. In another well known 85 form of grinder, the hammers are independent straight bars pivoted between a series of disks so that the shanks of the hammers occupy practically all the space between 90 the cutting ends and the peripheries of the disks, thus increasing the weight of the rotor, increasing the opposition of wind and material and requiring greater power to 95 operate than in the present form. In an 100 105 110

other form of hammer the operative edge is formed by a cross bar practically the width of the casing and the long bar head has no flexibility of action, as in my style.

5 In the form shown in this application, the flexibility of the operating edge is maintained, the space between said edge and the disks is left open, the reduced number of T-shanks required by the present form of T-head as compared with the independent hammers mentioned, cheapens the construction, increases the slicing action, reduces the opposition of wind and material and hence the driving power required.

10 15 While I have shown the single T-head and the intermediately located leg for said head as formed of a double flat bar, the hammer may be otherwise formed as long as the T head principle and the slicing action as 20 distinguished from the beating and crushing action is maintained as above described.

25 In all these forms of T hammers, the lesser dimension of both the head and the leg is presented to the material being operated on, and the slicing effect upon the material is similar to that of a stirrup hammer with the flat connecting cross bar and legs at the ends of the cross bar head.

30 This form of head secures cheapness in construction and the small surface of the

cross bar used as the operative edge increases the efficiency of the slicing action in passing through the material, making less wind opposition and causing less expenditure of power.

35

I claim:

1. In a machine of the character described; a pivotal slicing hammer, consisting of a flat bar, bent so as to form a double flat top and double shank portions, said top 40 extending laterally beyond said shank and having its upper portion beveled and extending in front of its lower portion on both front and rear forming cutting edges thereon, said shank having openings therein. 45

2. In a machine of the character described; a pivotal slicing hammer consisting of a flat bar, bent so as to form a double flat top and double shank portions, said top 50 extending laterally beyond said shank, said shank having openings therein,—the width of said bar being relatively much greater than the thickness so that the lesser dimension of the bar in leg and head is presented to the material being operated on, and 55 slices through the material, substantially as described.

In testimony whereof I have affixed my signature.

EDWARD B. CAMPBELL.
